CABLE EQUALIZING MECHANISM.

Application filed July 28, 1931. Serial No. 553,511.

This invention is a novel cable equalizing mechanism; the embodiments herein disclosed being designed more especially for the equalizing of elevator cables, although the principles are applicable to analogous purposes where a number of cooperating cables are to be so combined as to share substantially equally the total strain applied to the entire group.

The general objects of the invention are to afford a cable equalizing mechanism of improved efficiency, and of great strength and durability combined with simplicity and inexpensiveness of construction. A particular object is to afford in an accurate and practical manner an equal distribution of the load or strain upon the several cables supporting the load, which cables may travel over a drum, sheave, etc., and are liable to inequalities of tension due to error in mounting, wear of cables or drum, and unequal elongation of cables in operation. Other and more detail objects and advantages of the present invention will be explained in the hereinafter following description of an illustrative embodiment thereof or will be understood to those conversant with the subject. To the attainment of such objects and advantages the present invention consists in the novel cable equalizing mechanism and the novel features of operation, combination and construction herein illustrated or described.

In the accompanying drawings Figure 1 is a perspective elevation of an elevator car, its operating cables, and an equalizing mechanism interposed between the car and cables in accordance with the present invention.

Fig. 2 is what may be considered a front elevation of the mechanism with certain parts cut away to show structural details beyond.

Fig. 3 is a right elevation taken in section on the vertical section line 3—3 of Fig. 2.

Fig. 4 is a top view and section taken on the horizontal line 4—4 of Fig. 2.

Fig. 5 is a front elevation of a detail of construction showing a modification.

Fig. 6 is a diagrammatic representation of a modification of the arrangement shown in

Figs. 1—4.

Fig. 7 is a right elevation taken in section on the line 7—7 of Fig. 8, of a modified cable equalizing mechanism.

Fig. 8 is a top view and section taken on the section line 8—8 of Fig. 7.

The invention is applicable to the cables of elevators or other objects wherein a considerable number of cables share the load and are to assume equal strains or tensions. In the form shown in Figs. 1—4 six cables are assumed, which is the usual number in ordinary elevators, but the principles are applicable to other plural numbers of cables, for example eight cables, as will be described in connection with Fig. 6. Referring first to the cables and the elevator, Fig. 1 shows the cables arranged in pairs, namely a left outside pair a' , a^2 , a second or right outside pair b' , b^2 , and a middle pair c' , c^2 . Each cable may have a conventional type of terminal anchor device and block or swivel, and by these devices each pair of cables is shown attached to the two ends of a short equalizer lever, as is the usual practice with an even number of cables. Thus the cables a' and a^2 are pivotally connected to an equalizer lever a which in turn is centrally fulcrumed at the top of a tension member, connector or bar A. The parts a , A and others will herein be referred to as movable parts, in the sense that during any equalization they are subject to movement relatively to the elevator or car; and the elevator and parts rigidly connected with it will herein be referred to as fixed parts.

As already stated, in referring to an elevator it is intended to include any equivalent load, such as a counterweight. In referring to cables it is intended to include ropes, chains and the like or even rods or inflexible connectors employed in ways to transmit either tension or compression.

The second pair of cables b' , b^2 are similarly shown connected to an equalizer lever b pivoted at the top of a tension member or bar B; and the cables c' , c^2 are pivoted at the ends of an equalizer lever c , centrally pivoted at the top of tension member C. The cables of each pair are mutually equalized by the short equalizer lever connecting them, and the remaining problem is the connection of

the three tension bars A, B and C to the car in a way to give practical equalization as between them. The upper portion of a passenger elevator Y is shown, and as usual this may be supported in a square frame of structural members, the upper members or cross head of which comprise a pair of beams or channels Z, Z which are fixed parts, and on which the equalizing mechanism hereof is mounted.

Some of the fixed parts mounted on the cross head Z, Z include the plates or frame parts 10 arranged at the inner sides of the channels, facing each other, and secured by bolts 11 extending through the frame plates 10 and channels, each plate also having a horizontal flange 12 extending beneath each channel Z, taking the load and giving security against the shearing of the bolts 11. Extending from each frame plate 10 to the opposite one are a number of cross rods 13, six being shown near the upper edge and six near the lower edge of the plates. These rods may be inserted in apertures in the plates before the plates are inserted between the channels, and the plates and rods form a strong fixed interior frame.

The rods 13 serve not only as cross connections between the frame plates, but they are so arranged as to constitute guides or confining means for the several tension bars A, B and C respectively. Thus, as clearly seen in Fig. 2 each tension bar is closely confined by a pair of cross rods 13 not only near the top but near the bottom of the interior frame. The bars are thus held rigidly in correct vertical position during any up and down equalizing movements. At the foot of each tension bar is shown a cross pin 14, constituting a stop or safety device adapted to impose a limit to any downward movement of the car relatively to the group of cables, the stop pins 14 being arranged to be contacted by the cross rods 13 if the latter should descend excessively. If desired, compression springs 15 may be interposed between the stop pin 14 on each tension bar and the cross rods 13 thereabove, as shown in Fig. 5, this being a modification wherein the spring not merely cushions the safety or stopping action, but imposes a constant pressure tending in some cases to modify and improve the equalization of strain as between the several cables.

The operative connections between the tension members or bars A, B and C and the fixed parts or frame will next be described.

At the right or inner side of the left bar A is shown a toothed rack 17. The middle bar C at its left side is formed with a similar rack or teeth 18, facing the rack 17. The right bar B is shown as provided with rack teeth 19 at its left or inner side, and facing the same the middle bar C has rack teeth 20 at its right side, all of these racks being vertically movable with the bars or connectors in the sense that they assume differing relative positions

when any stretch or other inequality in the cables occurs.

Between the rack 17 on bar A and rack 18 on bar C is shown a left gear member 22 meshing with both racks. In the embodiment of Figs. 1-4 this gear member is formed in two parts in order to afford correct ratios of movement and stress. Thus the gear member 22 has a gear portion or toothed segment 23 of small radius, meshing with the rack 17, and a toothed segment 24 of larger radius meshing with the rack 18, and at the axis has an axle 25 outstanding at the two sides. The gear member 22 is thus a floating gear running freely on the racks 17 and 18 during any relative movement between the racks, and with a center stud or axle, which axle however may be located differently in accordance with any changes in the relative lengths of radii of the two segments.

Similarly there is a right gear member 27, substantially symmetrical with the gear member 22, having teeth or a segment 28 engaging the rack 19 and a larger segment 29 engaging the rack 20, with an outstanding axle 30, constituting the center of both segments or series of teeth.

According to the present invention the gear members 22 and 27 do not float without control so as to receive unrelated movements with movements of the tension bars, but they are maintained in a certain relation to each other and with the fixed parts of the mechanism. This is shown as effected by means of a relatively long horizontal rocker or lever 32 capable of swinging about its center, with a longitudinal slot 33 engaging the left gear axle 25 and a symmetrical slot 34 engaging the right gear axle 30, so as to govern the relative movements of the two gear members, while permitting the axles to travel outwardly in the slots during any departure from the horizontal position shown. The rocker 32 is shown as composed of opposite side pieces, moving together. The center or fulcrum of the rocker is fixedly connected with the cross head or channels Z, and frame plates 10, for example by studs 35 projecting from central recesses in the frame plates and engaging in corresponding recesses at the centers of the opposite side pieces of the rocking lever, the studs 35 not extending through but terminating to leave space between the side pieces of the rocker for the accommodation of the middle tension bar C.

From the description given it will be seen that the entire weight of the car depends from the axle studs 35 of the rocker 32, and that this weight or load is thus transmitted to the rocker which in turn through its slotted ends pulls down upon the axles of the gear members 22 and 27, thus transmitting and distributing the load to and through the gear members to the racks 17, 18, 19 and 20, the load thus being transferred by the tension

members A, B and C to the small equalizer levers *a*, *b* and *c* and thence to the six cables: Assuming the case of an elevator weighing 6000 pounds this will be distributed by the 5 rocking lever 32 to the two gear members, each receiving at its axle a load of 3000 pounds. With the proportions shown the load on each gear member is distributed unequally to the two racks engaging it. Thus taking the left 10 gear member 22 its short or left radius is only half the length of its long or right radius. The load of 3000 pounds will thus be apportioned, 2000 pounds being delivered to the rack 17 and bar A and 1000 pounds to the 15 rack 18 and bar C. Similarly at the right 2000 pounds will be delivered to the rack 19 and bar B and 1000 pounds to the rack 20 and bar C. The net result is that each of the tension bars A, B and C received 2000 pounds 20 of load, and in each case this is redistributed so that each individual cable receives 1000 pounds of load. At the same time the movable parts are all relatively vertically shiftable for equalizing purposes, so that inequalities 25 of length of cable or the like are promptly neutralized, while at the same time the proportions and distribution of load are accurately maintained.

The gear members 22 and 27 may be considered 30 as floating oscillators or rockers pivoted at the respective ends of the main rocker, since the readjusting motion is usually a short one, the outer and inner ends of each oscillator tilting slightly up or down, and the 35 bars A, B and C constituting a system of vertical tension members operatively engaging the respective ends of the oscillators.

The modification of Fig. 6 is applicable in a case where eight cables may be used. The 40 arrangement of cables is substantially similar to Figs. 1-4, except that the middle pair of cables *c'*, *c*² is replaced by two pairs of cables *d'*, *d*² and *e'*, *e*², connected respectively by equalizer levers *d* and *e* from which are hung 45 tension bars D and E. In this case the loads carried by the respective gears 22^x and 27^x are not to be apportioned unevenly, since each gear cooperates with a pair of racks, namely racks 17^x and 18^x engaged by gear 22^x and 50 racks 19^x and 20^x engaged by gear 27^x. The gears in this case are simple circular gears with equal radii of teeth engaging both racks, and as before both gears have their axle studs 55 engaging in the slotted ends of the rocker 55 lever 32, the center or axle of which is fulcrumed on the load or elevator. Assuming a load of 8000 pounds on the axle 35 this will be distributed to the gears equally, with 4000 pounds on each. The radii being equal each 60 gear will distribute to its load to its two racks, imposing 2000 pounds on each rack, which is communicated by the tension members or bars A, E, D and B and the equalizer levers *a*, *e*, *d* and *b*, to impose 1000 pounds on each 65 cable; while at the same time there is complete

freedom for relative vertical adjustment to offset inequalities of length of cable.

It is believed to be new with this invention, in one aspect, to provide a system of longitudinal rack members and gear members in mutual engagement, interposed between the tension elements that are supported by the cables and the load element or elevator, and adapted to undergo play for equalization while distributing the stresses to the cables; 70 particularly with the axes of the gear members in parallel relation and the rack and gear members compactly assembled within a frame attached to the elevator. In this aspect a modified embodiment is shown in Figs. 7 and 75 80 arranged for equalizing six cables supporting an elevator, although under the principles disclosed the number of cables could be increased or diminished.

In Figs. 7 and 8 tension members or bars A, 85 C and B are indicated, as in Figs. 1 to 4, each of these however at its lower end being forked to receive a gear. The elevator cross head or fixed channels Z, Z may be as previously described. Between the fixed 90 channel beams is shown a frame, having substantial height and width, to fit securely between the beams, and of high strength. This frame comprises longitudinal or vertical portions 41 at both sides and cross pieces 42 at 95 the top and bottom, with extensions through which the frame is secured by bolts 43 to the flanges of the channels. The longitudinal portions 41 are machined to serve as guides for the racks to be described, and the cross pieces are apertured for the vertical movements of the racks.

Sliding within the frame 41, 42 is shown a compactly arranged or nested system of racks, arranged at the two opposite sides of the frame space, with the teeth of each facing inwardly or toward those at the opposite side. Secured near one corner of the frame space, by pins 44 is a vertical rack 45 having fixed relation to the channel beams and elevator. At the opposite side is a rack 46, which may be designated as a floating rack as it is not attached to the frame. Part of the rack 46 faces the rack 45, but the rack 46 is of double width, its other half facing part of the rack 47. The rack 47 is at the same side as the rack 45, and it is a floating rack partly facing the rack 46 and partly facing the rack 48. Rack 48 is a floating rack adjacent the rack 46 and partly facing the rack 47 and partly the rack 49. The floating rack 49 is adjacent the rack 47 and partly faces the rack 48. A fixed rack 50 is secured by pins to the frame in a position to face part of the floating rack 49.

Intermediate the several racks is a system of gears engaging the racks and for convenience arranged at two levels, for example three gears at an upper level and two at a lower level. The first gear 51 is an upper gear, 120 125

hung from the fork at the lower end of the tension bar A, and engaging the racks 45 and 46. The second gear 52 is a lower gear and engages the racks 46 and 47, this gear having its axle in fixed relation to the elevator. The gear 53 is an upper gear, hung from the fork of tension bar C and engaging the racks 47 and 48. Gear 54 is a lower gear fixed to the elevator and engaging the racks 48 and 49. Gear 55 is an upper gear mounted in the fork of tension bar B and engaging with rack 49 and fixed rack 50. Mounted on the lower cross piece 42 of the frame is shown a projection or bearing 57 supporting an axle 58 on which the fixed gears 52 and 54 rotate.

This combined assemblage gives effective equalizing action for the three tension bars and therefore the six cables which support them. The floating racks 46, 47, 48 and 49 are capable of up and down sliding within the frame during any equalizing adjustments of the cables. The racks 46 and 48 are for convenience shown at substantially the same adjustment or height while the racks 47 and 49 are shown at the same height, but different from that of the racks 46 and 48. Each of the four floating racks may be provided at its lower end with a stop pin 60 and at its upper end with a similar stop pin 61, these serving as safety devices to limit the extreme movements of the racks, in the sense already described in connection with stop pins 14.

With the mechanism shown in Figs. 7 and 8 any relative vertical movement as between the positions of the three upper gears, representing changes of position or length of the tension bars A, B and C, or the cables supporting them, will be immediately distributed by the system of racks and gears, and the load in any adjustment being taken up equally by the bars and cables. By the fixed racks 45 and 50 the elevator may be said to be hung from the upper system of gears, but under the control of the floating racks 46 to 49, which serve to communicate the adjustment and load between the three upper gears and the two fixed racks, the two lower gears also receiving and transmitting part of the load to the racks and upper gears.

The modification of Figs. 7 and 8 may be described as involving a system of longitudinal racks, two of which are engaged by each of the floating gears carried by the terminals of the tension members, and two of which racks are fixed to the load while the remainder are floating racks, together with gears fixed to the load, one less in number than the floating gears, each engaging two floating racks. The first fixed rack 45 meshes with the first floating gear 51, which in turn meshes the first floating rack 46, which in turn meshes the first fixed gear 52, which gear meshes the second floating rack 47, which in turn meshes the second floating

gear 48, and so on for any number of gears and racks, until the last floating gear engages the second or last fixed rack.

The specific embodiment shown in Figs. 1-4 may be described as comprising three tension bars, the middle one carrying two toothed racks and the outer ones each one toothed rack facing a middle rack, with two floating gears each meshing one middle rack and an outer rack and transmitting to the racks the load received from the rocker; and each gear member comprising two portions, one having twice the radius of the other, the shorter meshing with an outer rack and the longer with a middle rack, whereby the three tension members all receive the same load stress or tension. The form shown in Fig. 6 comprises four tension members supported by the cables each carrying a toothed rack, the racks facing each other in pairs, and the two floating gears each meshing with two of such racks constituting a pair and transmitting thereto the stress received equally by the gears from the rocker.

A cable equalizing mechanism has thus been described embodying the principles and advantages of the invention; but as various matters of operation, combination and construction may be modified within the principles hereof it is not intended to limit the invention to such matters except to the extent recited in the claims.

What is claimed is:

1. Cable equalizing mechanism comprising a rocker centrally pivoted on the load with arms extending laterally at both sides, a floating oscillator or gear member pivoted at each end of the rocker, and a system of vertical tension members supported by the cables and operatively engaging both ends of each floating oscillator.

2. Cable equalizing mechanism comprising a rocker centrally pivoted on the load with arms extending laterally at both sides, a floating oscillator or gear member pivoted at each end of the rock, and a system of vertical tension members supported by the cables and operatively engaging both ends of each floating oscillator; the floating oscillators or gear members having their arms or ends so proportioned as to distribute equal fractions of the total weight to the several tension members.

3. Cable equalizing mechanism comprising a rocker pivoted on the elevator with oppositely extending arms, a floating gear member mounted on each arm of the rocker, and a system of vertical racks supported by the cables and engaging both sides of each floating gear member.

4. Cable equalizing mechanism comprising a plurality of tension members supported by the cables, and carrying toothed racks, a plurality of gear members each meshing with two of such racks and transmitting stress

- thereto, and a rocker mounted on and carrying the load and having opposite arms connected with the gear members to distribute the load stress thereto.
5. Mechanism as in claim 4 and wherein each gear member comprises portions or segments engaging two racks, such gear portions having radii proportioned inversely to the number of cables to which they transmit load respectively.
6. Cable equalizing mechanism comprising three or more tension members supported by the cables, and carrying four or more toothed racks, guide means on the load holding the racks in longitudinal paths, a plurality of floating gear members each meshing at its opposite sides with two of such racks, and mounted on the opposite arms of a rocker, and said rocker, the same mounted on and carrying the load and having opposite arms connected to shift with the respective gear members.
7. Cable equalizing mechanism comprising three tension members supported by the cables, the middle one carrying two toothed racks, and the outer ones each carrying one toothed rack facing one of the middle racks, two floating gear members each meshing with one middle rack and another rack and transmitting stress thereto, and a rocker mounted on and carrying the load and having equal arms connected with the gear members to distribute the load stress equally thereto; each gear member comprising two toothed portions one of twice the radius of the other, the shorter meshing with an outer rack and the longer with a middle rack, whereby the three tension members all receive the same stress or tension.
8. Mechanism as in claim 6 and wherein each gear member has an outstanding axle stud, and the rocker arms have slots engaging such axle studs and permitting relative play as the rocker rocks.
9. Cable equalizing mechanism comprising four tension members supported by the cables, and each carrying a toothed rack, facing each other in pairs, two floating gears each meshing with a pair of such racks and transmitting stress thereto, and a rocker mounted on and carrying the load and having opposite arms connected with the gears to distribute the load stress equally thereto.
10. Cable equalizing mechanism, comprising a plurality of tension members supported by the cables, a load element supporting the load, a floating gear carried by each tension member, a system of longitudinal racks, two of which are engaged by each floating gear, and two of which racks being fixed to the load and the remainder being floating racks, and gears fixed to the load, one less in number than the floating gears, and each engaging two floating racks.
11. Mechanism as in claim 10 and wherein the first fixed rack meshes the first floating gear, which also meshes the first floating rack, which also meshes the first fixed gear, which also meshes the second floating rack, which also meshes the second floating gear, and so on until the last floating gear engages the second fixed rack.
12. Mechanism as in claim 10 and wherein there is a frame carried by the load, the racks being arranged in two facing rows nested within the frame, and the gears being arranged on parallel axes between the rows of racks.
13. Cable equalizing mechanism comprising a plurality of tension elements supported by the cables, a load element supporting the load, a system of longitudinal rack members interposed between the tension elements and load element, said rack members arranged in facing pairs and adapted to undergo relative longitudinal sliding adjustment, and a system of gear members engaging the facing rack members of each pair and compelling longitudinal adjustment of such facing rack members in opposite directions.
14. Mechanism as in claim 13 and wherein there is a frame in which the several rack and gear members are completely assembled, said frame carried by the load, and being provided with longitudinal guide means for the sliding of the rack members and parallel axles for the gear members.
- In testimony whereof, this specification has been duly signed by.
- LE ROY H. KIESLING.
